INSULATING BUSHING FOR HIGH TENSION CONDUCTORS

Application filed January 2, 1929. Serial No. 329,747.

This invention relates to insulating bushings particularly adapted for use in electrical precipitation.

In this type of device, suspended materials, such as dust, fumes, mists, and the like are precipitated from a stream of gas in which they are suspended by passing the stream of gas through an electrical field maintained between discharge electrodes and collecting electrodes at a high difference of potential (the well known Cottrell process). These electrodes are usually mounted in a chamber, the discharge electrode or electrodes being connected to a conductor, which must be carefully insulated, for which purpose porcelain insulators are used.

In practice it is necessary to keep these insulators relatively clean, as otherwise not only does wasteful leakage of current occur over the unclean surfaces, which prevents the maintenance of an effectively high precipitation voltage, but local discharges or "arc-overs" occur over their surfaces, which cause shattering of the insulators, with resultant damage to the high tension system which may cause the bending of high-tension members, the breaking of other insulators and long shut down of units until repairs are made.

According to this invention, these difficulties are obviated by surrounding the high-tension leads at the places where they pass into the precipitator chamber with bushings made from gypsum or like material, which can be cheaply made, quickly replaced, and do not, like porcelain, shatter when an arc-over occurs. These bushings can be made practically gas-tight, and thus, in some cases, there is obviated the necessity of hoods or gas-tight insulator compartments.

The invention will be readily understood from the accompanying drawings in which

Fig. 1 is a diagrammatic vertical section through the upper part of one form of electrical precipitator;

Fig. 2 is a top view of the bushing and supporting bar for the high-tension conductor;

Fig. 3 is an elevation of one-half of the insulator;

Fig. 4 is a plan view of Fig. 3;

Fig. 5 is an elevation of the other half of the insulator;

Fig. 6 is a plan view of a cover-piece; and

Fig. 7 is a side view of Fig. 6.

The bushing is made of gypsum, plaster of Paris, asbestos meal or cement; cement mixed with lime, "Sil-o-cel", or magnesia; cementitious compounds containing wood or paper fiber; or the material known on the market as "Gypsum wood pulp plaster", which is understood to be a mixture of plaster of Paris, lime and wood fiber. All of these materials can be easily molded when mixed with water and will set and dry at ordinary temperatures, and when dry have insulating qualities. All these materials may be characterized as self-setting in contradistinction to porcelain-like materials which have to be baked at high temperatures.

Bushings made of these or like materials have the physical property that they do not shatter, as does porcelain, when an arc-over takes place through the material or along its surface. Those materials which contain fibrous binders, such as wood or asbestos fiber, have an increased resistance to cracking or pulling apart when the outer and inner surfaces of the bushing are subjected to different temperatures.

The bushings are preferably made in two sections as shown in Figs. 3 to 7. One hollow half section B has a semi-cylindrical outer surface, has an integrally formed cover portion H, provided with a semi-circular opening I, and grooves F, in its edges. The corresponding half section E is shown in Fig. 5 and is like section B, except that it is somewhat shorter and has a separate cover portion D, also provided with an opening I and grooves F. Each of the sections is preferably provided on its interior with deep valleys or corrugations to give larger leakage surfaces. These valleys may be omitted or may be located on the outside of the bushing.

When casting a bushing, a mixture is made of gypsum, or other suitable material, and water of a consistency to permit pouring from a pail. A form having a shape corresponding to the exterior surface of the bushing is provided with a core to form the interior

of the bushing, and the mixture is poured into the thus formed mold. The whole is allowed to set for a sufficient time, say a half hour. After this, the core and form are removed and the sections allowed to "cure" for about 5 a week, after which they are ready to be assembled.

In assembling, a layer of about one inch of cement, as shown at O, Fig. 1, is spread 10 on the top of the chamber and around the opening for the high-tension wire. Sections like B and E are then put into place and held together by any suitable clamping rings 15 M, shown in dotted lines in Fig. 1. The grooves F are then filled with a thin mixture 20 of gypsum, and the clamps are drawn tight. After this, the top-piece D is cemented onto section E, thus completing the bushing with 25 the top sections closely surrounding the high tension lead, and making a practically gas-tight joint therewith. After the cement has 30 set, these clamping rings are removed. The cover section D can be removed at any time to inspect the interior without disturbing the 35 remainder of the bushing.

This new type of bushing therefore has the advantages that it constitutes a relatively 30 gas-tight closing means at the high tension inlet points; does not crack under the temperature variations encountered; after an arc-over has occurred, does not form current leakage paths; dissipates absorbed moisture rapidly enough to prevent short-circuit through 35 the moisture; allows high tension discharge system supporting porcelain insulators to be located where they will not accumulate moisture and fail mechanically from electrical 40 leakage; cheapens construction by eliminating insulator hoods and gas-tight compartments; and reduces maintenance costs by reducing the frequency of insulator cleaning 45 and replacing of broken insulators. The location of the bushings with respect to the high tension system for electrical precipitators of the Cottrell type is shown in Fig. 1, in which J, J are porcelain insulators supporting a conducting bar K, from which are suspended the high tension leads N, N, passing 50 through the bushings L, L, which surround openings in the top S of the precipitator chamber. Supported by these leads N, N, is another conducting bar P, which in turn supports the discharge electrodes Q, Q, arranged between collecting electrodes R, R, 55 according to common practice. T is a supplemental insulator compartment, which may be omitted.

We claim:

60 1. A bushing for high tension electrical systems consisting of a hollow cylindrical structure and having openings at top and bottom for the high tension lead, the bushing comprising a plurality of sections composed of a self-setting cementitious insulat-

ing material, said sections being cemented together with similar cementitious material.

2. A bushing for high tension electrical systems composed of a self-setting cementitious insulating material, comprising a half 70 section provided with a cover-piece, another section without a cover-piece and a half-cover piece mounted on said second section.

3. A bushing as claimed in claim 2 in which the abutting faces of the sections are provided 75 with grooves filled with cementitious material.

4. A high tension electrical system comprising a porcelain insulator, a high tension conductor carried by said insulator, and a hollow bushing having a separable top portion surrounding said high tension conductor, said bushing being composed of a self-setting cementitious insulating material, the top portion being cemented to the remaining portion 85 with similar cementitious material.

In testimony whereof, we affix our signatures.

ALEXANDER N. CROWDER.
AARON N. SIMMONS.
